HEEL

Edward E. Leu, Chicago, Ill.

Application May 20, 1941, Serial No. 394,313

6 Claims. (Cl. 36—39)

This invention relates to interchangeable heels for boots, shoes, or like foot wear.

One object of my invention is to provide a heel plate which is readily attachable to, or removable from, an ordinary heel being held thereon interchangeably and against displacement.

A further object of my invention is to provide a heel plate which when attached will rotate automatically and will be subjected to automatic rotation when worn by a person having shoes 10 equipped with my invention; it being subjected to rotation by the motion or stride of movement employed in the walking gait by a person walking.

Another object of my invention is to provide a rotating heel plate which will relieve the pain to which the toes of a person walking may be subjected while walking. For example, when the foot is put down on the pavement with the ordinary heel which does not rotate, and which in arresting the shoe itself by frictional contact will cause the toes of the foot to continue to move forward relatively, within the shoe, and thus cause the tips of the toes to contact the inner tip of the shoe, and when toes are tender or sore, the irritation will be further aggravated by walking and by the action which is provided by ordinary heels. With my particular heel plate or disc, which rotates while in motion when the foot within the shoe is put down on the sidewalk or pavement, the rotation of the heel takes up some of the momentum and allows the shoe to move forward with the foot so that there is no relative displacement of the foot with respect to the shoe. This action will protect the toes from being subjected to painful contact from irritation, and from pain caused by contact within the tip of the shoe as a result of walking.

These and other like objects are attained by the novel construction and combination of parts hereinafter more fully described and set forth in the appended claims.

In the accompanying drawing forming a material part of this disclosure:

Fig. 1 is a perspective view of a section of the heel portion of a shoe showing my invention attached thereto.

Fig. 2 is an enlarged longitudinal cross-sectional view on the line 2—2 of Figure 4.

Fig. 3 is a longitudinal cross-sectional view on the line 3—3 of Figure 2.

Fig. 4 is a transversal cross-sectional view on the line 4—4 of Figure 2.

Fig. 5 is an exploded perspective view of mem-

bers 21 and 12 comprising important elements of my invention.

Fig. 6 is a fragmentary plan view showing the action taking place when the rotating disc or plate is to be removed from assembly.

Referring more particularly to Figure 1, I show a shoe generally designated by the numeral 7, having an upper member 8, a sole member 9, and leather heel portion 10, to which my invention is secured. My invention being generally designated and comprised of members 11 and 12.

Referring more particularly to Figure 2, it will be noticed that the member 11 is shaped like a standard rubber heel and is differentiated from a standard rubber heel by being provided with the recess 13 having an arcuate semi-circular portion to accommodate the rotating plate or heel member 12, and is further provided with an elongated recess 34 in order to accommodate the sliding element 31.

The heel proper is provided with two rubber button structures 37 cast integrally with the heel member 11, and by virtue of which it is secured to the heel portion 10 of the shoe 7 by means of screws 24, and at the rear portion by a shorter screw member 23. The member 11 is provided with the elongated recess 34 and a deeper recess 39 as indicated for purposes presently to be described.

Within the recess 34 is mounted the member 31 having a bent portion 29 leading to a handle member comprised of sections 36 and 28, which may be grasped in the fingers and pulled to the dotted position indicated in Figure 2.

To the member 11 is secured a guide plate 25 which is formed approximately as shown, having anchoring lugs 27 and 26. This member is attached preferably by placing it in the mold prior to injecting into the mold the plastic rubber when the heel member 11 is to be made. The guide member 25 is provided with a guide hole 42 to accommodate the portion 36 of the member 31.

In like manner, bushing member 19 is placed 45 in the mold prior to the injection of the plastic material. The bushing member 19 is provided with anchoring flanges 20 indicated in Figure 2 in order to locate and rigidly secure the same to the heel member 11 when it is formed.

The disc member 12 is provided with a rotating stud having a head 15, a reduced shoulder 16 which is journaled in the bushing or sleeve 19 and which is provided with a further reduced shank portion 17 and a head portion 18. The head portion 18 is either of the same or a lesser

diameter than the reduced body portion 16 so that it will readily pass thru the opening within the sleeve or bushing member 19 when it is assembled. The head 15 of the rotating stud is sufficiently large to insure stability and also to provide proper anchoring means for securing the rotating stud firmly within the rotating heel member 12.

The rotating heel member 12 is provided with a series of arcuately shaped recesses or grooves 14 which are provided for the purpose of conveying a lubricant such as graphite to the intermediate bearing plate member 21 which is made preferably of metal, and is provided with a series of holes 22 which will permit the graphite or lubricant to pass thru on the opposite side of the plate member and thus furnish lubrication between the surfaces 40 and 41 respectively, when the heel member 12 is subjected to rotation with respect to the stationary heel member 11.

In Figure 3, the sectional view further elucidates the specific structure indicated in Figures 1 and 2, indicating clearly the shoe 7, comprising its component elements, namely, the upper 8, the sole 9, the heel 10 and the inner sole 38.

In Figure 4, the means provided for removing the disc plate 12 is more clearly indicated and it is comprised of an enlarged opening 32 in the member 31 having a reduced opening 33. The opening 32 is large enough to clear the head 18 of the stud embedded in the rotating disc 12, whereas the reduced portion 33 is large enough to permit the shank 17 of the stud to work freely and to rotate freely therein.

The member 31 is held in place by tensioning means such as the spring 30 indicated in Figure 2 and Figure 4. The spring has a tendency to keep the heel member, normally, in locked position. When the spring is compressed by virtue of a pull on the handle member 28 to the right as shown in Figure 2, the enlarged opening 32 will align itself with the stud head 18 thus permitting removal of the plate member 12.

The handle member 28 is to be retained in this position when it is desired to replace the disc plate 12, then it is released, whereupon the spring 30 expanding to its normal shape will cause the member 31 to move to the left, thus bringing the reduced opening 33 underneath or below the head 18 causing a rotatable locking effect between the disc member 12 and the heel member 11, permitting free and easy rotation as heretofore explained. The member 21 is provided with an opening 35 to clear the reduced body 16 of the rotating stud so as to permit it to rotate freely therein.

In attaching or removing a disc heel 12 after it has been substantially worn and is no longer useful, it is merely necessary to pull the handle member 28 to the dotted position indicated in Figure 2, compressing the spring 30, and causing the enlarged opening 32 to align co-axially with the head 18, the opening 32 being larger than the diameter of the head 18 will permit removal of the disc plate member by allowing the stud to which it is secured to drop freely therethru, and likewise in assembling another heel disc member 12 to the heel 11, it is merely necessary to compress the spring 30 by pulling the handle member 28 and aligning the rotating stud within the bushing 19, and then releasing the handle member 28 which will cause the spring 30 to move the member 31 to the left, thus aligning the reduced recess 33 with the stud member 18. Thus it can be seen that the heel disc 12 is free

to rotate by virtue of its rotatable attachment, and furthermore, because of the lubricating means provided by the plate 21 and the lubricant which may be passed freely therethru, thru the openings 22 thereof; hence the graphite which is placed within the groove 14 passing thru the openings 22 and lubricating the bearing surfaces 40 and 41 respectively so as to provide free and easy rotation.

10 Not only is it possible by virtue of the rotation of the heel to maintain an even and level disc plate member as well as even wear resulting from constant walking, but when it is sufficiently worn, it may be interchangeably replaced with another heel member of the same size almost instantaneously and without requiring an experienced cobbler to perform the work.

15 It is also to be noted that I have provided this construction for people who are subjected to pain in the toes because of the fact that their walking gait subjects the foot to a resultant movement of the foot with respect to the shoe, thus causing the toes to be pounded frequently and continually against the tip of the shoe, thus aggravating a painful or sore foot condition.

20 Altho, I have enumerated numerous advantages, the actual showing embodied herein may suggest other advantages which have not been specified or mentioned. I believe I have indicated a preferred form of the embodiment of my invention and described the same succinctly, in order to produce the results enumerated, and inasmuch as I believe that my disclosure is susceptible of many modifications, alterations and 25 improvements, I reserve the right to all changes, alterations, modifications and improvements which come within the scope and spirit of my invention, and within the purview of the foregoing description; my invention to be limited only 30 by the subjoined claims.

35 Having thus described and revealed my invention what I claim as new and desire to secure by Letters Patent is:

1. In a device of the character described, in 40 interchangeable removable and replaceable heel means rotatably secured to fixed heel means, the said removable and replaceable heel means adapted to receive limited and intermittent rotation imparted to it by a wearer equipped with 45 the said device when walking, the said removable and replaceable heel means provided with arcuately shaped lubricant transfer recesses.

2. A device of the character described comprising, fixed heel means secured to foot wear, 50 and interchangeably removable and replaceable heel means rotatably secured to the said fixed heel means, the said removable and replaceable heel means adapted to receive limited and intermittent rotation imparted to it by a wearer 55 equipped with the said device when walking, the said removable and replaceable heel means provided with arcuately shaped lubricant transfer recesses.

3. In a device of the character described 60 comprised of fixed heel means and interchangeably removable and replaceable heel means rotatably secured to said fixed heel means, lubricant transfer means intermediately disposed between the said fixed heel means and the said removable and replaceable heel means, comprising, a plate member rotatably mounted and provided with perforated means adapted to pass a lubricant between respective adjacently contacting surfaces of said fixed heel means and said inter-

changeably removable and replaceable heel means.

4. A device of the character described comprising, fixed heel means secured to foot wear, interchangeably removable and replaceable heel means adapted to receive limited and intermittent rotation imparted to it by a wearer equipped with the said device when walking, and lubricant transfer means interchangeably disposed between the said fixed heel means and the said removable and replaceable heel means, comprising, a plate member rotatably mounted and provided with perforated means adapted to pass a lubricant between respective adjacently contacting surfaces of said fixed heel means and said interchangeably removable and replaceable heel means.

5. In a device of the character described com-

prised of fixed heel means and interchangeably removable and replaceable heel means rotatably secured to said fixed heel means, spring urged locking slide means slidably secured to the said fixed heel means and adapted to hold rotatably and releasably the said removable and replaceable heel means.

6. A device of the character described comprising, fixed heel means secured to foot wear, 10 interchangeably removable and replaceable heel means adapted to receive limited and intermittent rotary motion imparted to it by a wearer equipped with the said device when walking, and spring urged locking slide means slidably secured to the said fixed heel means and adapted to hold rotatably and releasably the said removable and replaceable heel means.

EDWARD E. LEU.
